UNITED STATES PATENT OFFICE.

EMILE LETARTE, OF LEOMINSTER, MASSACHUSETTS.

DESIGN FOR A COMB.

Application filed April 30, 1923. Serial No. 6,007. Term of patent 3½ years.

To all whom it may concern:

Be it known that I, EMILE LETARTE, a citizen of the United States, residing at Leominster, in the county of Worcester and State of Massachusetts, have invented a new, original, and ornamental Design for a Comb, of which the following is a specification, reference being had to the accompanying drawing, forming part thereof.

Fig. 1 is an edge view of a comb showing my new design;

Fig. 2 is a front view, and

Fig. 3 is an end view.

I claim:

The ornamental design for a comb as shown.

EMILE LETARTE.
